UNITED STATES PATENT OFFICE.

ÖIVIND MOSS, OF BERGEN, NORWAY.

DRAFT REGULATOR.

Application filed March 30, 1926. Serial No. 98,590.

The invention relates to draft regulators for furnaces and especially those of the type of boiler furnaces, where the products of combustion are conducted through fire tubes to a chamber from which flues lead the gases elsewhere. The invention is particularly useful in marine boilers, an embodiment of which is here indicated.

It is an object of the invention to enable the regulation of the draft in such manner that there will be unobstructed access of air to the fuel, while the escape of the combustion gases is regulated according to the requirements of the service, or exigencies.

Another object is to prevent the gases of combustion from being cooled off against the walls of the soot box, but are retained closely against the boiler front with the purpose of more efficiently utilizing the heat in the gases. At the same time the gases will still serve to induce proper draft in the chimney or funnel by reason of their expanded state.

It is also a purpose to present a novel construction in a particular apparatus for accomplishing the ends of the invention, especially applicable to an ordinary boiler installation without requiring modification of the boiler or flue structures, or necessitating more space other than is ordinarily occupied by such installations.

Additional objects, advantages and features of invention may be apparent from the construction, arrangement and combination of parts involved in the embodiment of the invention, as will appear from the following description and accompanying drawings, in which—

Figure 1 is a front elevation of a boiler 40 and soot box 11 in which my invention is installed, one door 12 of the box 11 being removed and parts broken away to show elements behind.

Figure 2 is a fragmentary vertical sectional view longitudinally of the boiler, showing the parts of Figure 1.

Figure 3 is a top view of the regulator structure isolated.

Figure 4 is a detail rear elevation of the 50 fastening for the swinging plate section in the device.

Referring more particularly to the details, a bipartite plate (a) including upper and lower sections, ordinarily formed of 55 quarter-inch sheet iron is suspended from two horizontal angle irons (b) by a slidable

mounting including trunnions (c) of a head piece (h) to be described. The plate is shaped to conform to the soot box as far as practicable, and the lower section may be further subdivided if required. The plate (a) is shaped particularly to correspond to the group form of the tubes 13 of the boiler, which are indicated behind the plate in Figure 1. The lower section of the plate 60 in the present instance is equal in area to the transverse cross sectional dimensions of one group of tubes and corresponds to the shape of the group as viewed from one end. This lower section of the plate (a) 65 is connected with the upper section by hinges (e) in such manner that the lower section may be swung outwardly through the door opening of the soot box toward a horizontal position where it will not interfere with the operation of tube cleaning devices, removal of soot, or access to the boiler head for other purposes. The hinge members are preferably connected by pintle bolts and nuts for practical reasons. 70

Means is provided to adjust the plate (a) from without the soot box consisting in a flat-threaded screw (f) with a correspondingly grooved sleeve (g) riveted to the upper section of the plate (a) which is reinforced by the beforementioned head piece (h) extending along its upper edge and having the trunnions (c) formed thereon. The screw is provided with an apron or flange (i) held between thrust rings (k) 80 and (l) on each side of the flange and which are secured together and to the wall of the soot box over the door opening.

To prevent the adjustment of the regulator from being changed by casual or ordinary mischievous operation, the screw is formed with a squared outer end (m) requiring the use of a loose crank handle for its operation.

Adjustment of the plate (a) with respect 100 to the boiler is secured by rotating the screw so as to draw or push the sleeve, thereby moving similarly both sections of the plate (a) as one from or toward the boiler, while held parallel to the boiler head, the tenons (c) sliding on the bars (b).

The lower section of the plate is held releasably in rigid alinement with the upper section by a locking contrivance consisting of a screw and hand nut (n), the nut being 110 at the front of the plate, the screw passing therethrough and having a cross piece (o).

which may be drawn against a vertically slotted plate (*p*) fixed to the upper section of the plate (*a*) or when turned to aline with the slot in the plate (*p*), may swing forwardly with the lower section of the plate (*a*).

By the construction and arrangement shown the draft may be regulated at the outlet of the fire tubes from the boiler, and thereby a substantial improvement in utilization of the fuel attained, for, by checking the discharge of the gases to the stack or funnel they can be prevented from escaping at too high a temperature.

15 Further, it is made possible to turn a greater account the heating surfaces of combustion chambers and smoke pipes, as, by permitting unobstructed access of air properly to the fire and checking of combustion products, a slower passage of the various gases through the boiler is secured, together with more thorough combustion, through mingling of air and gases occurring within the boiler.

20 It will be understood that the arrangement may be modified in various ways within the limits of the invention.

I claim:—

1. A draft regulator for boilers of the character described comprising a furnace structure, a sectional plate including an upper section having a slideable mounting for movement toward and away from the boiler head, and fixed in parallelism to said head, means to move the plate, the lower section of the plate being hinged to the upper, and releasable means to secure the lower section in fixed operative relation to the upper section, the said means to move the plate comprising a revoluble member alined with the path of operative movement of the plate and having screw threaded engagement with the movable element of the mounting of the plate and exposed for operation exteriorly of the furnace structure.

2. In a draft regulator of the character described, for boiler furnaces, a plate parallel to the boiler head, two guides arranged parallel to the longitudinal axis of the boiler and at the upper side of the path of the plate, tenons carried by the plate resting on the guides, an interiorly threaded sleeve fixed upon the outer side of the plate, a screw engaged in the sleeve and mounted against longitudinal movement and exposed exteriorly of the furnace structure for operation.

3. A draft regulating device for boiler furnaces of the character described, comprising a plate having an upper section mounted for movement in parallelism toward and away from the boiler head and a lower section hinged thereto, a T headed bolt engaged through the lower section having its head at the inner side of the plate, and a slotted plate fixed on the upper section of the first named plate and extending downwardly to receive the head of the bolt therethrough in one position and to be clamped by the head of the bolt in an alternate position, means bearing on the front of the said lower section to draw the bolt against the slotted plate, and means to move the upper section as described.

4. In a boiler having fire tubes a soot box and clean out doors alined with tube groups; a damper plate having a mounting for movement to and from the boiler head within the soot box in parallelism to the boiler head and including a principal portion having a hinge mounting and being shaped, positioned, and constructed to swing outwardly from the boiler through the clean-out door there-adjacent, releasable means to fix the said principal portion against movement on the hinge mounting, and means to move the plate toward and away from the boiler head.

In testimony whereof I affix my signature.

OIVIND MOSS.
